CONVEYER

Harry D. Lathrop, Chicago, Ill., assignor to The
Lathrop-Paulson Co., a corporation of Illinois

Application December 9, 1936, Serial No. 115,033

16 Claims. (Cl. 198—213)

This invention relates to a conveyer and more particularly to a conveyer in which spiral conveying means are employed.

An object of the invention is to provide a simple and effective conveying apparatus in which few parts are employed and by which accurate means for raising and lowering objects can be employed while maintaining control of the speed of descent or ascent of the objects. A further object is to provide a vertical conveyer in which articles may be lifted or lowered within a very small space while at the same time controlling the speed of movement of the object. A further object is to provide mechanism by which an object can be lowered from one floor of a building in a steady manner to a lower floor or landing and vice versa, lifted from a lower floor to a higher floor by the same mechanism.

A further object is to provide a conveyer equipped with an automatic feed, the conveyer being made in sections, making it possible to load or discharge on any floor or point. Another object of the invention is to provide a spiral conveyer with means for eliminating friction or for increasing friction. A further object is to provide a conveyer consisting of a plurality of spirals, one of the spirals being of less diameter than the other or others.

A further object of the invention is to provide a conveyer spiral and a plurality of stop spirals whereby the capacity of the conveyer spiral is greatly increased. Another object is to provide roller or other suitable anti-friction means for supporting the spiral conveyer or stop spiral intermediate their ends so that they may extend to substantial heights without danger and without requiring excessively heavy material. Other specific objects and advantages will appear as the specification proceeds.

The invention is illustrated, in a preferred embodiment, by the accompanying drawings, in which—

Figure 1 is a broken view in elevation of a conveyer embodying my invention; Fig. 2, a top plan view; Fig. 3, a sectional view, the section being taken as indicated at line 3 of Fig. 2; Fig. 4, a plan view of sections of the conveyer adapted to be secured together and clamped about the spiral post and also showing supporting rollers; Fig. 5, a side view in elevation of the structure shown in Fig. 4; and Fig. 6, a plan view of a modified form of the invention, plural stop spirals being employed in conjunction with a conveyer spiral.

In the illustration given in Figs. 1 to 3 inclusive, A designates a conveyer spiral; B, a stop

spiral; C, driving mechanism; and D, automatic feed mechanism.

The spiral conveyer A preferably consists of a post or shaft 10 having a conical lower point 11 received within a concave bearing in pillar 12. The shaft 10 is secured at its top within bearing 13 and is provided with a collar 14 which is fixed to the shaft and rests upon bearing 13.

A spiral track 15, formed in segments, is secured to the shaft 10. The track 15 may be of any suitable shape for receiving and conveying barrels, packages or any other desired objects. Preferably, the track is slightly tilted toward its center so as to prevent the objects carried within the track from falling off the track during the descent or ascent. The conveyer track, as shown more clearly in Fig. 1, is provided with an outer edge ledge 16 and with an inner concavity 17. Preferably the track is cast in short segments integral with a half-sleeve and the same is secured to the shaft 10 by bolting the sleeve carrying the track to a complementary sleeve 18, each of the sleeves being provided with outwardly extending ears 19 which are brought into alignment and secured together by bolts. It will be understood, however, that the track may be secured to the post in any suitable manner and may be in one piece, if desired, or in segments as illustrated.

In the illustration given, an upper floor is indicated by the letter E and a lower floor is indicated by the letter F. The spiral shaft 10 extends through both floors. However, the spiral track 15 terminates just short of the upper floor E and just above the lower floor F. In usual operation, it will probably be desired to install a conveyer (not shown) below the lower end of the track 15 to receive and carry away in a horizontal plane the articles lowered by the conveyer.

The stop spiral B may also be formed of any suitable materials and constructed in any suitable way. In the illustration given, a vertical shaft 20 is employed, the lower conical end 21 of the shaft being received within a bearing carried by pillar 22. The upper end of the shaft is provided with a collar 23 which is fixed to the shaft 45 and rests upon bearing 24. A spiral rod 25 is secured to the shaft 20, as shown more clearly in Fig. 1 by means of arms or struts 26. The stop spiral B is of less diameter than the conveyer spiral A. However, its threads do extend inwardly between the threads of the spiral A so as to cause the two sets of threads to intermesh, the B spiral providing a stop within the track or path of the spiral A. In other words, the threads of spiral B are staggered with respect to 55

the threads of spiral A so that half threads of the spiral B extend between half threads of spiral A and each half thread of spiral B which extends between threads of A provides a stop which will prevent objects or barrels carried by track 15 from moving downwardly faster than spiral B rotates. In the lifting operation, each stop prevents backward movement of the object above it carried by track 15 and cooperates with track 15 in elevating the object.

Both shafts 10 and 20 are operated together, that is, in the same direction, and at the same speed. Each of the shafts is provided below floor 12 with a sprocket 27, the sprockets being connected by chain 28.

The driving mechanism C may also be of any suitable type or construction. In the illustration given, a motor 29 drives a horizontal shaft 30 provided with a worm which meshes with worm gear 31. Worm gear 31 is fixed to shaft 10. Chain 28 connecting the sprockets 27 causes shafts 10 and 20 to rotate at the same speed and in the same direction. It will be observed that in the construction shown, the entire driving mechanism 25 is located below the floors and out of the way of the conveyer mechanism proper.

The automatic feed mechanism D may be of any suitable type or construction. As shown more clearly in Figs. 2 and 3, parallel conveyer tracks 30 32 are provided for carrying barrels, cases, etc., toward a large opening 33 in the floor E. The opening 33 is directly over the spiral conveyer track 15. Below the floor 13 is provided a hinged stop member 34 which is pivotally secured to abutment 35 and ordinarily pressed in an upward direction by means of spring 36. The pivoted member is provided with two upwardly extending stop arms 37 which are ordinarily pressed above track 32 under force of spring 36. Member 34 is provided with a depending platform 38 which is adapted to be engaged and depressed by cam 39 which is secured to the lower edge portion of track 25.

In the operation of the construction shown in Figs. 1, 2 and 3, a barrel or case is slid down track 32 toward opening 33 in the floor E. The barrel or case is stopped by the upwardly extending arms 37. Meanwhile, motor 29 is turning both of the spiral shafts 10 and 20 in the same direction and at the same speed. As the spiral track 15 rotates, cam 39 is brought into engagement with the member 38, thus depressing it to the position shown in Fig. 3 and thereby releasing the case or barrel which then falls through the opening 33 onto the upper portion of track 15. The case or barrel immediately falls along track 15 into contact with the stop spiral 25 which checks its fall, and as the two spirals rotate, the stop spiral rod 25 permits the case and barrel to gradually drop downwardly in a vertical plane along track 15 as track 15 rotates. In other words, the case moves downwardly in a vertical plane as the carrier spiral A rotates, the rod spiral 25 being brought steadily into contact with the object so as to control positively its rate of fall. If the two spirals are driven in the opposite direction, the barrel or case is lifted, the stop spiral rod following the object as it moves upwardly in a vertical plane along spiral track 15. As already stated, any suitable mechanism may be provided below the trackway 15 for carrying away products delivered thereon by trackway 15 or for feeding objects to said trackway when the articles are to be elevated.

In the above operation, it will be observed that

the stop spiral B provides between each of the threads of the conveyer spiral A a stop arm or projection which is adapted to hold an article on the trackway 15 and cause it to rise or fall, depending upon the direction of movement of the two spirals.

In the construction shown in Figs. 4 and 5, I provide a plurality of vertical rollers 40 which are supported in bracket arms 41 at their tops and bottoms and in such a manner as to engage the edge of three or more threads of the spiral. The rollers 41 bear against the sides of the spiral and support it against lateral sway or bending. By this means the spiral may be extended through several floors of a building and operated as a continuous vertical conveyer. The vertical rollers 40 may also be employed in conjunction with the stop spiral B when it is extended for substantial heights.

In the construction shown in Figs. 4 and 5, the track 15 is formed in segments, one segment 15^a being cast integrally with a clamping collar 18^a. The clamping collar 18 on the opposite side thereof consists simply of the collar portion and does not carry any of the track 15. However, the collar 18^b, which is just below the collar portion 18^a, is integrally provided with a track portion 15^b. It will be seen that the track portions 15^a and 15^b form a complete spiral or thread. It will be understood that the clamping collar (not shown) opposite 18^b and directly below 18^a, is like collar 18; that is, it does not have integrally formed therewith any portion of the track. It will thus be seen that the clamping collars are made up, as viewed in a vertical position, of alternating 35 collar segments without track portions and collar segments with track portions integrally formed therewith. This construction permits quick and ready assembly. Also, it permits the user to break off the track readily on any floor or point without 40 in any way affecting the remainder of the elevator. Assuming an elevator passing upwardly through three floors, should the operator desire to convey articles from the third floor and discharge them on the second, this can be readily 45 accomplished by removing one or more segments of the spiral track near the second floor, a receiving receptacle or conveyer being placed adjacent the termination of the spiral track. If it is desired then to carry the articles all the way from the third floor to the first floor or from the first floor to the third floor, the removed track segments can be replaced and the conveyer will then carry the articles all the way from the first to the third floor, or vice versa.

For the purpose of utilizing all the space of the spiral track 15, a plurality of stop conveyers may be used, as illustrated in Fig. 6. The advantage of this construction is that the spiral B on one side will maintain an object in one vertical line on track 15 of spiral A, while the stop spiral B on the other side will maintain an object in another vertical plane on track 15 of spiral A, thus utilizing more space on track 15. It will be understood that track A may be completely surrounded by B spirals, if desired.

The raised flange or rim 16 of the trackway tends to eliminate friction to some extent. It will be understood, however, that the conveyer track 15 may be provided with raised portions 70 or rods to eliminate friction; or, if some friction is desired, the track may be substantially flat. When the spiral is used for lowering objects, practically no power may be required, the driving mechanism being used simply as a governor or as 75

a means for positive control of the rise or fall of the objects at a predetermined speed. Of course, the pitch of the spiral will determine how far packages will be lowered or lifted by one full revolution thereof, and such pitch may be modified to meet individual requirements of conveyers. Automatic feed and delivery of the packages is rendered easy by the elimination of the spiral at the feeding or discharge point. In such operations, round or barrel-shaped objects may roll into the spiral by gravity and also may leave the spiral by gravity, thus leaving the discharge opening always unobstructed. Of course, as stated above, suitable discharge conveyers and feeding conveyers may be employed in connection with the spiral as desired.

Where the spiral conveyer extends through several floors, I prefer to have the automatic feed mechanism D located on each of the floors so as to feed directly onto the spiral. This does not require any change in the spiral A, it being necessary only to add the cam 39 to trip the feed mechanism so as to discharge the object onto the spiral track 25 at a point near the stop spiral B. Thus, when the spiral extends through a number of floors, operators may feed the single spiral as it rotates on any one of the floors, the automatic feed mechanism D permitting the barrels or boxes, etc. to be fed at the proper place and time. While I have shown a specific feed mechanism, it will be understood, however, that any suitable mechanism for this purpose may be employed or, if desired, the objects may be fed by hand into the conveyer on any one of the floors or at other points intermediate the height of the spiral conveyer A.

My new conveyer, while capable of lifting and lowering large quantities of articles, occupies a minimum of space and eliminates the necessity for a large area heretofore found necessary for gravity conveyers, etc. The inclination of the track inwardly tends to throw the articles against the inner post and prevents any danger of their falling off. By this construction the trackway may be made even smaller than the object which is conveyed thereby.

In the operation of the vertical spirals, it will be noted that the function of the stop spiral is primarily that of maintaining an object in substantially one vertical plane as the conveyer spiral rotates. The configuration of the stop spiral is such that it follows the article moving upwardly or downwardly while maintaining it in substantially the same vertical plane. This being true, the object or article has to rise or fall depending upon the direction of rotation of spiral A.

While I prefer to employ a stop spiral, as illustrated, it will be obvious that other means may be employed to move upwardly and downwardly in a vertical plane adjacent spiral A and maintain an object thereon in substantially the same vertical plane. It is believed unnecessary, however, to describe such equivalent structures because the same will be readily apparent to those skilled in the art.

The foregoing detailed description has been given for clearness of understanding only, and no unnecessary limitations should be understood therefrom, but the appended claims should be construed as broadly as permissible, in view of the prior art.

I claim:

1. In a conveyer, a pair of screw members positioned adjacent each other so that the threads

of one member extend within the outer periphery of the threads of the other, said screw members being rotatably mounted, and means for moving said screw members together and in the same direction whereby the thread portion of one member serves as a rising or falling abutment adjacent the thread portion of the other member. 5

2. In a conveyer of the character set forth, a pair of spiral conveyer members arranged in intermeshing position and mounted for rotation, 10 and means for rotating said members at the same speed and in the same direction.

3. A gravity conveyer of the character set forth, comprising: a pair of rotatably mounted spirals supported in vertical position, said spirals having 15 intermeshing threads, and means for rotating said spirals at the same speed and in the same direction whereby the thread of one spiral serves as a constantly receding stop for the other spiral.

4. In a gravity conveyer of the character set forth, a pair of intermeshing spirals supported in substantially vertical position for rotation, one of said spirals providing a track for receiving articles and the other of said spirals providing a stop whereby said articles are prevented from falling precipitously along said track, and means for rotating said spirals at the same speed and in the same direction whereby said stop spiral controls the rate of descent of the articles supported by said track spiral. 20 25

5. In a conveyer of the character set forth, a pair of spirals having intermeshing threads and supported in substantially vertical position for rotation, and means for rotating said spirals together and in the same direction whereby the 35 thread of one of said spirals serves as a lifting member while the thread of the other spiral serves as a track member.

6. In a conveyer of the character set forth, a pair of spirals having intermeshing threads, and 40 means for rotating said spirals together and in the same direction for lifting objects in engagement with the intermeshing threads of said spirals.

7. In a conveyer of the character set forth, a 45 vertically mounted member providing a spiral track upon which objects may be moved, a second member equipped with a spiral stop member intermeshing with said curved track whereby said stop member is maintained adjacent the path of 50 said track member so as to provide a stop for an object moving therewith, and means for rotating said two members at the same speed in the same direction.

8. In a conveyer of the character set forth, a 55 spiral conveyer member and a plurality of spiral stop members arranged in intermeshing position with said conveyer member, and means for rotating said spiral conveyer and stop members.

9. In a conveyer of the character set forth, 60 a conveyer spiral and a plurality of stop spiral members arranged in intermeshing position and mounted for rotation, and means for rotating said spirals together and in the same direction whereby objects are conveyed by said spiral conveyer in substantially vertical planes. 65

10. In a conveyer of the character set forth, a spiral conveyer member mounted for rotation, means for rotating said conveyer, means for maintaining an object carried by said spiral in 70 substantially one vertical plane as said spiral rotates, and rotatably mounted means engaging edges of said spiral and rotating therewith to brace said spiral.

11. In a conveyer of the character set forth, a 75

- pair of spiral conveyer members arranged in intermeshing position and mounted for rotation, means for rotating said members, and rotatably mounted rollers supported so as to engage and rotate with at least one of said spiral members.
12. In a conveyer of the character set forth, a spiral conveyer member mounted for rotation, means for rotating said member, means cooperating with said spiral for maintaining an object thereon in substantially a vertical plane for a portion of its travel as said spiral rotates, and rotatably mounted rollers engaging the lateral edges of said spiral for bracing the same.
13. In a conveyer of the character set forth, a pair of spiral conveyer members arranged in intermeshing position and mounted for rotation, one of said spiral members being of greater diameter than the other and providing a spiral track, and means for rotating said members at the same speed and in the same direction.
14. In a conveyer adapted for vertical movement of objects, a rotatably mounted member providing a spiral track upon which objects may move, means for rotating said member, means for loading said track at a point intermediate the height thereof, and spiral means for maintaining an object upon said track in substantially one vertical plane as said member rotates, said spiral means and spiral track being in intermeshing relation.
15. In a conveyer of the character set forth, a vertically mounted rotatable member providing a spiral track upon which objects may be moved, a second member rotatably mounted about an axis parallel with the axis of said spiral track and comprising a rod in the form of a spiral and extending within the periphery of said track, and means for rotating said members at the same speed whereby said rod serves as a moving abutment for preventing movement of said objects about the axis of said track.
16. In a conveyer of the character set forth, a pair of vertically mounted rotatable shafts, a spiral track mounted on one of said shafts and having a raised outer peripheral edge portion so as to retain objects thereon as the objects are raised or lowered on the track, a spiral rod about said other shaft and fixedly secured to said other shaft, said rod being adjacent said spiral track so as to block the movement of said objects along said track about the axis of the track, and means for rotating said track and said rod at the same speed.

HARRY D. LATHROP.
